Schenley Industries, Inc., New York, N. Y., a
corporation of Delaware

Application January 27, 1954, Serial No. 28,689

Term of patent 14 years

(Cl. D58—6)

To all whom it may concern:

Be it known that I, Ernest L. Du Pree, a citizen of the United States of America, residing at the city of Westport, county of Fairfield, and State of Connecticut, have invented a new, original and ornamental Design for a Combined Decanter and Closure Cap Therefor, of which the following is a specification, reference being had to the accompanying drawing, forming part thereof.

Figure 1 is a front elevational view of a combined decanter and closure cap therefor embodying my new design;

Figure 2 is a rear elevational view thereof;

Figure 3 is a bottom plan view thereof;

Figure 4 is a reduced fragmentary vertical sectional view, as seen on the line 4—4 of Figure 1;

Figure 5 is a cross-sectional view thereof, taken on the line 5—5 of Figure 1, on a reduced scale; and

Figure 6 is a top plan view of the closure cap portion removed from the bottle and taken on an enlarged scale.

I claim:

The ornamental design for a combined decanter and closure cap therefor, as shown.
